UNITED STATES PATENT OFFICE

2,536,452

DEFLECTING TOOL

Lee R. Leissler, Pasadena, Tex., assignor to Eastman Oil Well Survey Company, Denver, Colo., a corporation of Delaware

Application October 27, 1947, Serial No. 782,270

13 Claims. (Cl. 285—96.1)

1

This invention relates to new and useful improvements in deflecting tools.

The invention relates particularly to an improved knuckle or universal joint which connects the drill stem or pipe with a deflecting tool and is an improvement on the particular deflecting tool shown and described in the patent to Carpenter, No. 2,402,238, issued June 18, 1946.

It is one object of the invention to provide an improved deflecting tool which is adapted to be lowered into position within a well bore and then offset or inclined in a predetermined or known direction, whereby the tool will operate efficiently in controlled or directional drilling, as well as in well straightening.

An important object of the invention is to provide an improved tool of the character described which is arranged to be deflected and locked in a predetermined known direction while in the well bore, whereby after such deflection, the drill stem or pipe to which the tool is attached may be rotated to orient the tool in the desired direction in which drilling is to be continued and also whereby after proper orientation of said tool, subsequent drilling may be performed.

A particular object of the invention is to provide an improved deflecting tool wherein a gravity actuated means is associated with the tool for accomplishing deflection or inclination of said tool, said means being normally restrained against movement and being released when the tool is within the well bore so that the gravity actuated means assumes a predetermined position with respect to the tool, whereby when the means is again restrained from movement it causes a predetermined known deflection of said tool which permits accurate orientation of the tool within the bore; the construction of the tool being such that when subsequent drilling is carried out, the weight of the drill pipe is not imposed upon or carried by the gravity actuated means but rather, is transmitted directly to the drill tool, whereby the gravity actuated means is protected against undue load.

A further object of the invention is to provide an improved deflecting tool of the character described which is so constructed that the universal joint thereof is more or less self cleaning and will not lend itself to the accumulation of extraneous particles on the operating surface thereof, whereby more efficient operation will be assured.

Still another object of the invention is to provide an improved deflecting tool having all of the advantages of the deflecting tool shown in

2

the tool described in the patent to Carpenter, No. 2,402,238, and in addition being of a simplified construction whereby assembly and disassembly of the tool is facilitated.

5 The construction designed to carry out the invention will be hereinafter described together with other features of the invention.

The invention will be more readily understood from a reading of the following specification and 10 by reference to the accompanying drawing, wherein an example of the invention is shown, and wherein:

Figure 1 is a transverse, vertical, sectional view of a deflecting tool constructed in accordance 15 with the invention and showing said tool in the position which it assumes during lowering of the tool within a well bore,

Figure 2 is a transverse, sectional view of the universal joint of said tool and showing the parts 20 in a position with the gravity actuated orienting means released,

Figure 3 is a view similar to Figure 1 and illustrating the tool in drilling position,

Figure 4 is a horizontal, cross-sectional view 25 taken on the line 4—4 of Figure 2,

Figure 5 is a horizontal, cross-sectional view taken on the line 5—5 of Figure 2, and

Figure 6 is an enlarged detail illustrating a modified form of orienting member.

30 In the drawings, the letter D designates the usual rotatable drill pipe or stem which is adapted to be lowered through the well bore W. The drill stem has a drill bit E connected to its lower end by means of the improved knuckle or universal joint A, whereby the bit E may be deflected to various angular positions relative to the drill stem. As will be explained, the drill stem is adapted to be lowered downwardly through the well bore to the lower end thereof, and the bit E is arranged to be deflected into a known or predetermined direction from the vertical. The bit is locked or held in such deflected position so that the pipe or stem D may be rotated to properly orient the bit, after which 40 a drilling operation in the desired direction may be accomplished.

The improved joint A includes an outer annular body or shell 10 which may have reaming blades 10a formed on its exterior surface. 45 The body or shell has an axial bore 11 at its lower portion and said bore is counterbored or enlarged at 12 whereby an internal annular beveled seat 13 is formed therein. The upper end of the counterbore is formed with vertically extending grooves or recesses 14 which are located

diametrically opposite each other. Vertically extending grooves or recesses 15 are also formed in the body at the lower portion thereof, said grooves being cut in the bore 11.

An inner shell or sleeve 16 which has its upper end threaded onto the lower end of a connecting sub 17 is coupled to the drill pipe 10 by means of said sub and said inner shell or sleeve has its lower portion disposed within the upper end of the outer shell or body 10. The extreme lower end of the sleeve 16 is formed with an annular seating surface 18 which under certain conditions, as will be explained, is adapted to engage the annular seat 13 within the outer body 10. The sleeve 16 is rotatably coupled to the outer body by means of radial connecting pins 19 which extend outwardly from the sleeve and which engage within the upper radial grooves or recesses 14 in said body. By observing Figures 1 to 3 it will be seen that the depth of the recess is greater than the projection of the pins 19, whereby the outer body 10 may swing or incline from the axis of the inner sleeve or shell 16 without breaking the rotatable connection formed by the engagement of the pins 19 within the grooves 14.

The inner shell or sleeve 16 has an axial bore 20 extending entirely therethrough and nearer the lower end of said bore an internal annular shoulder 21 is provided. Below the shoulder 21, the wall 21a of the bore is nared or inclined outwardly toward the lower end of the sleeve, this inclined surface terminating adjacent the annular seating surface 18 at the lower end of the sleeve. A ball member 22 is mounted within the bore 20 of the inner shell or sleeve 16 and has its upper spherical surface engaged by a cylindrical socket element 23. The element 23 has its lower end formed with a semi-spherical socket 24 in its lower surface and an axial bore 25 extends upwardly from said socket to the top of the element. A suitable packing ring 26 encircles the socket element and seals off the space between said element and the bore 20 of the inner shell or sleeve. A spacer collar 27 is disposed within the bore 20 above the socket element 23 and normally the upper end of said collar is spaced from the lower end 17a of the coupling 17. A coil spring 28 of considerable strength has its lower end engaging the upper surface of the socket element 23 while its upper end engages an annular shoulder 29 formed within the bore 17b of the coupling 17. The spring 28 exerts its pressure to constantly urge the socket element 23 into firm engagement with the upper surface of the ball member 22.

The ball member has its lower portion cut away to form an external annular surface or shoulder 30 and as is clearly shown in Figure 1, the shoulder 30 overhangs the internal annular shoulder 21 which is provided in the lower portion of the inner shell or sleeve 16. An orienting ball 31 is disposed between the shoulder 30 on the ball member and the shoulder 21 within the inner sleeve 16, said ball being supported upon the latter shoulder 21 which forms a race or annular support therefor. The ball member 22 is provided with an integral depending shank 32 which extends downwardly through the bore 11 of the outer body or shell 10 and said shank is adapted to be rotatably coupled to the outer body by means of a pair of diametrically opposed keys 33 which engage within recesses 34 in the shank and also within the grooves or recesses 15 which as explained, are provided within the bore of the outer body 10. The outer body is supported in

position on the shank 32 by means of a supporting collar 35 which is threaded onto the shank and which abuts the lower end of the body 10, as is clearly shown in Figure 1. The depending shank 32 of the ball member 22 has the drill bit E attached to its lower end and said shank and ball member are formed with an elongate axial bore 36 extending entirely therethrough. This bore has its lower end communicating with the usual circulating passages of the bit E, while its upper end communicates through the bore 25 of the socket element 23, bore 20 of the inner sleeve 16 and bore 17b of the coupling 17 with the bore of the drill pipe D. With this arrangement the usual drilling fluid may be circulated downwardly through the drill pipe and through the joint A and to the bit E during the drilling operation.

In the use of the deflecting tool, the orienting or gravity actuated ball 31 will be disposed between the shoulder 21 of the inner shell or sleeve 16 and the shoulder 30 provided on the ball member 22. The coil spring 28 acting downwardly on the socket element 23 and ball member 22 will urge the shoulder 30 of said ball member into contact with the orienting ball 31 and since said ball is located at only one radial point on said shoulder, the pressure of the spring 28 will cause the ball member 22 to be rotated within the socket 24, with the result that the shank or stem 32 of the ball member will be inclined from the axis of the drill pipe and inner shell. This position of the parts is illustrated in Figure 1 and it is in this position that the deflecting tool is lowered downwardly through the well bore W.

The tool is lowered through the well bore until the drill bit E engages the lower end of the bore or a cement plug (not shown) which may have been introduced into the well bore at the point at which the deflection drilling is to occur. When the bit E engages the lower end of the bore, continued lowering of the drill stem causes the inner shell 16 to move downwardly with respect to the ball member 22 and downward movement of the shell is ultimately halted by the engagement of the lower end of said shell with the internal seat 13 within the outer shell. This position of the parts is illustrated in Figure 2 and the downward movement of the inner sleeve 16 with respect to the ball member 22 disengages the shoulder 30 from the gravity actuated ball 31, whereby said ball may roll around its supporting shoulder or race 21 to the low side of the well bore. It is noted that when the seating surface 18 at the lower end of the inner sleeve 16 engages the internal shoulder 13 of the outer shell, the lower end 17a of the connecting sub 17 has engaged the upper end of the spacer collar 27 so that further sliding movement of the socket element 23 within the bore 20 of the sleeve 16 is prevented.

After the orienting ball 31 has rolled around to the low side of the well bore, the drill stem is lifted upwardly a sufficient distance to disengage the bit E from the lower end of the well bore. When this occurs the coil spring 28 forces the socket element 23 downwardly and this in turn moves the ball member 22 downwardly with respect to the sleeve 16. As the ball member is moved downwardly, one point on its shoulder 30 engages the orienting ball 31 and the remainder of the shoulder tends to move downwardly into engagement with the supporting shoulder or race 21. This action results in a cocking or inclining of the shank or stem 32 which carries the de-

fecting tool. Obviously since the orienting ball 31 is disposed opposite the low side of the well bore, the direction of inclination will be with the drill bit E moving toward the low side of the bore. Thus, it is known that the bit is projected in a direction toward the low side of the hole and since a previous well survey will give the compass direction, the subsequent rotation of the drill pipe will orient the bit and locate it in the desired direction.

Following orientation of the bit E, it is only necessary to again impose the weight of the drill pipe upon the unit and this again moves the inner shell or sleeve 16 downwardly so that its lower end engages the internal seat 13 within the outer body 10. At the same time the spacer collar 27 engages the lower end of the sub and at this time the spring 28 is under additional compression. Rotation of the drill pipe D will impart a rotation to the outer body 10 through the connecting pins 18 and their co-acting grooves or recesses 14. Rotation from the outer shell or body 10 is transmitted to the stem or shank 32 through the keys 33 and slots 15 and 34, whereby the bit E is rotated. The weight of the drill pipe D is transmitted directly through the inner sleeve 16 to the shoulder of the outer body and from the outer body through the supporting collar 35 directly to the shank 32 and bit E. Thus, there is no weight imposed on the joint which is formed by the ball member 22 and the socket and neither is there any weight imposed on the orienting ball 31.

It is noted that the race way or supporting shoulder 24 upon which the orienting ball 31 is movable is located at a point above the lower end of the inner sleeve or body. Any extraneous matter which may enter the joint will enter the upper end of the body 10 and will fall into the lower portion thereof, which lower portion will form a settling chamber. There is very little likelihood of any extraneous matter ever entering the space between the supporting shoulder 24 of the ball member. It will be recognized that any particles which might accumulate on the race or shoulder 24 might interfere with proper gravity orientation of the orienting ball 31. The device is exceptionally simple in assembly since it is only necessary to remove the supporting collar 35 in order to permit the outer body 10 to be slid downwardly and disengaged from the shank 32. The spring, socket element and ball member 22 may be easily removed by merely disconnecting the sub 17 and removing these parts from the upper end of the inner shell or sleeve.

In Figures 1 to 5 an orienting ball 31 has been illustrated as the orienting member but it is pointed out that other types of gravity actuated means may be employed for accomplishing the purpose of deflecting the joint. In Figure 6 a modified form of orienting member is illustrated. In this form the orienting member indicated at 49 takes the form of a collar or annular weighted member. The collar is mounted on suitable bearings 41 so as to be freely rotatable on the supporting shoulder or race 24. The upper surface of the collar is beveled to provide a high point 42 and adjacent this point, the collar is suitably weighted so that this high point on the collar will always fall to the low side when released for rotation. The operation is identical to that hereinbefore described. When the weight of the drill pipe is imposed upon the inner sleeve or shell 16, the shell is moved downwardly with respect to the ball member to free the rotatable

collar 40 for rotation. The high point 42 of said collar will roll around to the low side and after the weight of the drill pipe is relieved and the parts returned to their original position, the upper beveled or inclined surface of the collar will cause the shank 32 of the ball member to be cocked or inclined in accordance with the position of the high point 42 of the collar. As above stated, the collar 40 is preferably weighted opposite the high point 42 but this is not essential since the weight could be located at any desired radial point or in any angular position with respect to the high point. Thus, the weighted area of the ring would always fall to the low side of the hole and this would locate the high point 42 which controls the direction of cocking or inclination of the shank at any given location with respect to the low side. With such an arrangement, the bit could be deflected in a predetermined selected direction and rotation of the drill pipe to orient said bit after it has been cocked or inclined would not be necessary.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A joint adapted to couple a drill pipe with a drill bit including, an inner shell connected to the lower end of the drill pipe and having a socket therein, a ball member within said socket having a depending shank which is connected to the drill bit, gravity controlled deflecting means interposed between the ball member and socket including an element movable in response to gravity for causing a deflection of said ball member with respect to said socket, an outer body enclosing the lower portion of the inner shell and the upper portion of the depending shank of the ball member, and means for rotatively coupling the outer body to the shell and also to the shank, whereby rotation of drill pipe and inner shell imparts rotation to the depending shank and drill bit.

2. A joint adapted to couple a drill pipe with a drill bit including, an inner tubular shell connected to the lower end of the drill pipe and having an annular supporting shoulder in the lower portion of its bore, a movable socket mounted in the shell above said shoulder, a ball member within the socket and having a depending shank which extends downwardly from the bore of the inner shell and which is connected to the drill bit, gravity controlled means confined between the socket and supporting shoulder and functioning to cause deflection of the ball member within the socket in accordance with its position relative to the socket, and an outer body surrounding the inner shell and a portion of the depending shank and rotatively coupled to each, whereby rotation of the inner shell is transmitted through the outer body to the shank and drill bit.

3. A joint as set forth in claim 2, wherein the socket is maintained in engagement with the ball member by resilient means and also wherein the ball member and socket may undergo a limited longitudinal movement with respect to the inner shell to free the gravity controlled means for rotation in an inclined well bore, whereby the position of said gravity controlled means and therefore the subsequent deflection of the ball member 75 with respect to the socket is known.

4. A joint adapted to couple a drill pipe with a drill bit including, an inner tubular shell connected to the lower end of the drill pipe and having an annular supporting shoulder in the lower portion of its bore, a socket slidable within the bore of the shell above said shell, resilient means engaging the upper end of the socket for constantly urging the same toward said shoulder, a ball member engaged within the socket and having a downwardly facing shoulder on its lower portion, gravity controlled means rotatable on said annular supporting shoulder and normally confined between said shoulder and the shoulder on the ball member, the co-action between the gravity controlled means and the ball member functioning to deflect said member and its shank with respect to the inner shell, said ball member and socket being slidable within the bore of the shell against pressure of the resilient means and in a direction away from the supporting shoulder to release the gravity controlled means for rotation when the joint is within an inclined well bore, whereby said means will assume a predetermined position with respect to the low side of the well bore so that subsequent return of the ball member into engagement with said means will result in a predetermined deflection of said ball member and its shank, and an outer body surrounding the inner shell and a portion of the shank and rotatively coupled to said shell and shank, whereby rotation of the shell is transmitted through the body to the shank and drill bit attached to the latter.

5. A joint as set forth in claim 4, wherein the outer body is connected to the shank in co-axial relationship and also wherein the upper end of the body is recessed at its point of connection to the shell to allow for deflection of the shank with respect to the shell.

6. A joint as set forth in claim 4, wherein the outer body is connected to the shank by a key and slot connection and is connected to the inner shell by a pin and groove connection, with said groove having a depth greater than the length of the pin to allow inclination of the body with respect to the inner shell when the shank is deflected from or misaligned with said inner shell.

7. A joint adapted to couple a drill pipe with a drill bit including, an inner tubular shell connected to the lower end of the drill pipe and having an annular supporting shoulder in the lower portion of its bore, a socket slidable within the bore of the shell above said shell, resilient means engaging the upper end of the socket for constantly urging the same toward said shoulder, a ball member engaged within the socket and having a downwardly facing shoulder on its lower portion, gravity controlled means rotatable on said annular supporting shoulder and normally confined between said shoulder and the shoulder on the ball member, the co-action between the gravity controlled means and the ball member functioning to deflect said member and its shank with respect to the inner shell, said ball member and socket being slidable within the bore of the shell against pressure of the resilient means and in a direction away from the supporting shoulder to release the gravity controlled means for rotation when the joint is within an inclined well bore, whereby said means will assume a predetermined position with respect to the low side of the well bore so that subsequent return of the ball member into engagement with said means will result in a predetermined deflection of said ball member and its shank, release of the gravity controlled means

being accomplished by imposing the weight of the drill pipe on the inner shell when the ball member and its socket are held stationary by the engagement of the bit at the lower end of the ball member shank with the formation or other support in the well bore, subsequent deflection of the ball member and its shank being effected by relieving the shell of the drill pipe weight, and an outer body mounted on the portion of the shank and having its upper end enclosing the inner shell and rotatively coupled thereto, whereby rotation of the shell is transmitted through the body to the shank.

8. A joint as set forth in claim 7, wherein the gravity controlled means is a ball which rolls upon the supporting shoulder within the inner shell.

9. A joint as set forth in claim 7, wherein the gravity controlled means is a collar which is rotatably mounted on the supporting shoulder within the inner shell and wherein the upper surface of said collar is inclined or beveled to form a high point on said collar, said collar being weighted at one radial point thereon to cause rotation of the collar when in an inclined well bore and when the joint has been operated to release the same for rotation.

10. A joint adapted to couple a drill pipe with a drill bit including, an inner tubular shell connected to the lower end of the drill pipe and having an annular supporting shoulder in the lower portion of its bore, a socket slidable within the bore of the shell above said shell, resilient means engaging the upper end of the socket for constantly urging the same toward said shoulder, a ball member engaged within the socket and having a downwardly facing shoulder on its lower portion, gravity controlled means rotatable on said annular supporting shoulder and normally confined between said shoulder and the shoulder on the ball member, the co-action between the gravity controlled means and the ball member functioning to deflect said member and its shank with respect to the inner shell, said ball member and socket being slidable within the bore of the shell against pressure of the resilient means and in a direction away from the supporting shoulder to release the gravity controlled means for rotation when the joint is within an inclined well bore, whereby said means will assume a predetermined position with respect to the low side of the well bore so that subsequent return of the ball member into engagement with said means will result in a predetermined deflection of said ball member and its shank, release of the gravity controlled means being accomplished by imposing the weight of the drill pipe on the inner shell when the ball member and its socket are held stationary by the engagement of the bit at the lower end of the ball member shank with the formation or other support in the well bore, subsequent deflection of the ball member and its shank being effected by relieving the shell of the drill pipe weight, a supporting collar on the upper portion of the shank of said ball member, an outer body surrounding the upper portion of the shank and resting on the supporting collar, the upper portion of the bore of said body surrounding the inner shell, means for rotatably coupling the outer shell to the shank, and additional means for rotatably coupling the upper end of the body to said inner shell, said last-named means permitting inclination of the outer body with respect to the shell without breaking the rotative connection therebetween.

11. A joint as set forth in claim 7, wherein the

outer body is provided with an internal annular seat which is adapted to be engaged by the lower end of the inner shell after the shank and drill bit have been deflected and a subsequent drilling operation is carried out, whereby the weight of the drill stem is transmitted directly from the shell to the outer body and thence to the drill bit during the drilling operation.

12. A joint for connection in a drill stem, comprising a member having a ball and to which a drill bit is connected and a member having a socket and to which the drill stem is connected, said socket being above the ball when received therein, gravity controlled means for imparting a bending force to the joint at the ball and socket connection when the joint is in a predetermined condition, said gravity controlled means having an element movable in response to gravity and being positioned beneath said ball member and protected thereby, and means for driving the member having the ball by the member having the socket.

13. A joint for connecting a drill stem to a drill bit, comprising a ball and socket universal joint, gravity control means for causing a bending at the universal joint, means for coupling the parts of the universal joint together so that rotation of the drill stem will rotate the drill bit, and means embodied in said joint whereby when downward drilling forces are applied through said joint to the drill bit during drilling operations said forces will be transmitted through said joint without excessive engaging pressures being established between the ball and socket of the universal joint.
